UNITED STATES PATENT OFFICE.

EDWIN S. MILLER, OF BUFFALO, NEW YORK.

WRENCH.

1,137,884.

Specification of Letters Patent.

Patented May 4, 1915.

Application filed December 19, 1912. Serial No. 737,636.

To all whom it may concern:

Be it known that I, EDWIN S. MILLER, a citizen of the United States, residing at Buffalo, in the county of Erie and State of New York, have invented new and useful Improvements in Wrenches, of which the following is a specification.

This invention relates to wrenches and more particularly to wrenches of that character in which the head is provided with two jaws one of which is adjustable relatively to the other for adapting the same to screw nuts, bolt heads or the like of varying sizes for turning the same.

It is the object of this invention to provide an improved wrench of this character which does not require complete removal from the screw nut or bolt head upon changing the position of the wrench relatively to such nut or head but enables the shifting of the wrench circumferentially of the nut or head to be effected with a ratchet action, and which enables this action to be effected easily and without incurring any material increase in the cost of manufacture over wrenches as heretofore constructed.

In the accompanying drawings: Figure 1 is a side elevation of a wrench embodying my improvements and showing the same engaging the head of a hexagon screw bolt in the act of turning the wrench forwardly. Fig. 2 is a fragmentary longitudinal section of the same showing the position of the parts of the wrench while turning the same backwardly relatively to the bolt head for taking a new hold of the same. Figs. 3 and 4 are fragmentary longitudinal sections taken in the correspondingly numbered lines in Fig. 1. Fig. 5 is a fragmentary side elevation of the wrench showing the same provided with a form of handle different from that shown in Fig. 1 and also showing the manner in which its jaws engage with a square screw head or nut in the operation of turning the wrench forwardly. Fig. 6 is a view similar to Fig. 5 but showing the position of the parts when turning the wrench backwardly relatively to the screw nut or head for taking a new hold of the latter.

Similar characters of reference indicate corresponding parts throughout the several views.

1 represents the head of the wrench which may be of any suitable construction

and provided with a handle which may be arranged either at an angle to the longitudinal center of the wrench, as shown at 2 in Figs. 1 and 2 or parallel with this center, as shown at 3 in Figs. 5 and 6. At one end the head is provided on its outer side with an arm projecting laterally therefrom, this arm being preferably bifurcated and its members 4 separated so as to leave an intervening space between the same. On this arm is pivotally mounted one jaw of the wrench the axis of this pivotal connection being arranged transversely of the wrench so that this jaw can swing or turn in a plane parallel with the general plane of the wrench. In its preferred form this jaw has a contracted or narrow rear part 5 which is arranged between the members of the bifurcated arm and pivoted thereto by means of a transverse pin 6 and a wide front part 7 which provides a comparatively wide bearing face on the front side of this jaw for engaging the article to be gripped and also to form a shoulder which cooperates with a shoulder on the arm for limiting the inward swinging movement of the pivoted jaw on the arm. The face of the swinging jaw preferably comprises an outer straight portion 8 which is normally arranged lengthwise of the wrench and an inner inclined portion 9 extending inwardly and forwardly from the inner end of the straight portion 8, as shown in Fig. 1. The straight portion of the face of the pivoted jaw extends inwardly beyond the axis of its pivotal connection with the arm.

In its preferred form the means for limiting the inward turning movement of the pivoted jaw utilize the outer or rear side of the enlarged inner part of the jaw by constructing the same in the form of an angular stop shoulder 10 which engages with a correspondingly formed stop shoulder 11 on the inner or front side of the members of the arm, as shown in Fig. 1.

On the opposite end of the head is mounted another jaw 12 which is preferably mounted slidably on the head so that the same is capable of adjustment toward and from the pivoted jaw. This adjustable jaw is provided with a bearing or gripping face which preferably comprises an outer straight portion 13 which is arranged lengthwise of the wrench and opposite to the transverse outer face portion of the pivoted jaw, and

an inner inclined portion 14 arranged at the inner end of the straight portion 13 and opposite the inclined face portion of the pivoted jaw.

5 The adjustable jaw may be guided on the head in its movement toward and from the pivoted jaw in any suitable manner for the purpose of adapting the mouth or space between these jaws to screw heads or nuts of 10 different sizes, the means for this purpose shown in the drawings being preferred and consisting of a slide 15 carrying the adjustable jaw and moving in a guideway 16 formed in the head. The preferred means 15 for shifting the adjustable jaw toward and from the pivoted jaw comprises a rotatable worm 17 arranged within an opening 18 in the head of the wrench and engaging with a gear rack 19 on the inner side of the slide, 20 and a pivot pin 20 which is secured to the head and upon which the worm is journaled. The opposite sides of the worm are accessible from the exterior of the head so that the same may be engaged by the fingers and 25 turned in one direction or the other for causing the adjustable jaw to be moved toward and from the normally fixed but pivoted jaw.

For the purpose of turning a particular 30 size of hexagonal screw nut or head 21 the jaws of the wrench are adjusted relatively to each other so that the distance between the longitudinal outer faces of these jaws is equal or nearly equal to the width of two 35 parallel facets on opposite sides of the nut or head to be turned and the wrench is applied to this head or nut so that two diametrically opposite facets of the nut or head are received by the longitudinal outer parts 40 of the faces of the jaws while the inner converging facets of the nut or head are received or stand opposite the inclined inner or converging face portions of these jaws. Upon turning the wrench forwardly while 45 the parts are in this position the longitudinal outer face of the pivoted jaw bears against the adjacent part of the screw head or nut at a point inwardly from the axis of the pivoted jaw while the longitudinal face 50 of the adjustable jaw bears near its outer end against the adjacent outer part of the head or nut, as shown in Fig. 1, whereby the latter is compelled to turn forwardly with the wrench inasmuch as both jaws are practically rigid at this time relatively to the head. Upon turning the wrench circumferentially backward relatively to the screw 55 head or nut the rearward pressure exerted by engagement of the screw nut or head 60 against the pivoted jaw near its outer end which is outwardly beyond the axis of the pivot 6 causes this jaw to turn about its axis so that the outer part of the jaw swings rearwardly away from the opposing adjustable jaw while the inner part of the pivoted 65

jaw swings forwardly lengthwise outwardly relatively to the mouth of the jaws, thereby causing the space between the jaws to flare outwardly and the jaws to be partly withdrawn from the screw nut or head which 70 is being operated upon. While the jaws are thus partly released from the screw head or nut the same may be freely turned circumferentially relatively thereto in a backward direction until the longitudinal faces of the 75 jaws are again opposite two parallel facets of the screw head or nut and at this time the pivoted jaw will be again returned to its normal position by the pressure of the same against the screw nut or head and the two 80 longitudinal portions of the faces of these jaws may be engaged with the next following pair of diametrically opposite facets of the screw nut or head in the manner previously described, thereby interlocking 85 the wrench with the screw head or nut preparatory to turning the latter forward another step by means of the wrench. In this manner the screw head or nut may be turned intermittently by means of the 90 wrench with a ratchet action during which the wrench is at no time wholly withdrawn from the screw nut or head. Inasmuch as the wrench need not be wholly removed from this screw nut or head upon taking a new 95 hold of the head or nut the operation of either loosening or tightening a screw head or nut is greatly facilitated and can be effected in much less time than is required by the use of an ordinary wrench which 100 necessitates complete removal of the wrench from the screw nut or head for shifting the same from one pair of facets on the screw head or nut to another pair. Furthermore, by providing the wrench head with the pivoted jaw both jaws may be engaged with a 105 large area of the screw head or nut to be turned, thereby securing a firm engagement of the wrench with said article and permitting of exerting greater power on the article 110 for turning the same.

By providing the inclined inner face portions on the jaws the latter may be materially strengthened at these places and still provide the necessary clearance or space for 115 the reception of the innermost corner of a hexagon screw nut or head while turning articles of this shape.

By making the front part of the swinging jaw wide and the rear part thereof narrow 120 it is possible to provide a strong connection between this jaw and the head and at the same time present a bearing surface to the article to be turned equal in width and area to that of the adjustable jaw, thereby 125 enabling the wrench to obtain a firmer and stronger grip on said article and enable the latter to be turned easily and positively. Furthermore, by providing the swinging jaw and the arm of the head with co-operat- 130

- ing angular shoulders, these parts are caused to interlock in the normal position of the swinging jaw and prevent the latter from becoming displaced relative to the arm during the forward turning movement of the wrench independently of the pivot pin connecting the swinging jaw with the arm. It is also to be noted that by this construction of the jaws the inner part of their faces 10 form extended bearing surfaces for engagement with the object to be grasped in all positions of these jaws within the adjustable limits of the wrench instead of producing line contacts with the same.
- 15 When utilizing this wrench for turning screw nuts or heads 22 of square form, as shown in Figs. 5 and 6, the operation is substantially the same as that when turning hexagon or other forms of heads or nuts, 20 the only difference being that the converging space between the inner parts of the jaws is not occupied by any part of the screw nuts or heads when the latter are of square form.

I claim as my invention:

A wrench comprising a head having an arm at one end and a slot formed lengthwise in the outer edge of the head and said arm whereby the latter is divided into two members, a swinging jaw arranged in that portion of said slot between said arm members and pivotally connected therewith, a slide movable lengthwise within said slot at the opposite end thereof and provided with a jaw adapted to coöperate with said swinging jaw, and means arranged on said head for adjusting said slide and its jaw lengthwise in said slot, the inner parts of the faces of said jaws forming extended bearing surfaces for engagement with the object 40 grasped in all positions of these jaws within the adjustable limits of the wrench.

Witness my hand this 13th day of December, 1912.

EDWIN S. MILLER.
